UNITED STATES PATENT OFFICE.

LEWIS R. HEIM, OF DANBURY, CONNECTICUT.

WIRE-FEEDING MECHANISM.

1,119,510.

Specification of Letters Patent.

Patented Dec. 1, 1914.

Application filed February 3, 1910. Serial No. 541,808.

To all whom it may concern:

Be it known that I, LEWIS R. HEIM, a citizen of the United States, residing at Danbury, county of Fairfield, State of Connecticut, have invented an Improvement in 5 Wire-Feeding Mechanism, of which the following is a specification.

This invention relates to wire feeding mechanism particularly adapted for use in 10 staple driving machines.

One of the objects of the invention is to produce a wire feeding mechanism provided with means for interrupting the wire feeding functions when a predetermined quantity 15 of wire has been fed.

A further object is to provide means whereby the wire feeding mechanism may slip with respect to the wire when the feeding movement is interrupted.

With these and other objects in view the invention consists in certain constructions and in certain parts, improvements and combinations which will be hereinafter described and then specifically pointed out in 25 the claims hereunto appended.

In the accompanying drawings forming a part of this specification in which like characters of reference indicate the same parts in all of the views, Figure 1 is a front elevation of the machine complete; Fig. 2 a side elevation partly in section on the line 2—2 in Fig. 1 looking in the direction of the arrows; Fig. 3 a rear elevation; Fig. 4 a front elevation of the head with the face 30 plate removed showing the cutting off, forming and driving mechanisms in the raised or normal position; Fig. 5 a similar view showing the parts in the depressed position, the front block being removed; Fig. 6 a de- 35 tail vertical section on the line 6—6 in Fig. 4; Fig. 7 a view of the forming block detached; Fig. 8 a view similar to Fig. 4 showing the position of the parts at the instant of the cutting off operation; Fig. 9 a similar 40 view showing the position of the parts after the forming operation and before the driving operation; Fig. 10 a section on the line 10—10 in Fig. 9 looking in the direction of the arrows; Fig. 11 an elevation of the 45 former and cutter carrying block detached; Fig. 12 a plan view of said block; and Fig. 13 is a detail elevation of the feed pawl and ratchet and the pinion as seen from the right in Fig. 3.

Referring to the drawing, 20 designates the body of my improved stapling device,

said body being of approximate L-shape in side elevation to form a vertical head and an elongated rearwardly extended supporting base (see Fig. 2) adapted to rest upon 50 one side of a box or case to which a tag or label is to be attached. A plunger 25 is mounted to reciprocate within a suitable bore or guide 26. At the upper end of the plunger is a rounded head 28 which is 55 adapted to receive a blow or pressure of the hand in operation. Below the head is a shank 29 which is rigidly secured to the plunger and is provided with an arm 30 to which a slide 31 is rigidly secured, said 60 slide lying in a guide 32 in a carrying plate 111 forming part of the body and reciprocating with the plunger. A spring 33 bearing against the underside of the shank and against the body, the lower end of the 65 spring being preferably socketed in the body, acts to return the plunger and slide to their normal position after each operation. As this spring is not required to perform any feeding or other operation but 70 merely to return the operative parts to their normal position after an operation, it may be made relatively light and but little power is required to overcome it in use, thus adding greatly to the ease of operation of the 75 machine and reducing the power or force of the blow or the amount of pressure required to operate it.

The plunger is provided with a rack 34 which is engaged by a gear wheel 35 having 80 a relatively long convex sector indicated by 36. Gear wheel 35 meshes with a feed driving pinion 37 which is free to oscillate on a shaft 38 and is provided with a relatively short concave sector 109. Shaft 38 is journaled in the body and carries a feed ratchet 39 lying outside the pinion (see Fig. 3) and on the opposite side of the body (see Fig. 1) carries a gear wheel 40, which has formed integral therewith or rigidly secured there- 85 to an upper feed roll 41.

42 denotes a housing which is rigidly secured to pinion 37 and carries a spring-actuated sliding feed pawl 43 which engages ratchet 39. A forward or downward movement of the plunger therefore through gear wheel 35 and pinion 37 causes the feed pawl 43 to carry the feed ratchet 39 and with it shaft 38, gear wheel 40 and upper feed roll 41 forward a distance equal to one 90 tooth of the ratchet. When the operator's hand is removed from the plunger, gear 95

wheel 35 and pinion 37 will return the pawl backward over a tooth of the ratchet to its normal position. the pawl sliding forward to the engaging position after it has passed 5 a tooth of the ratchet in the backward movement.

44 denotes the lower feed roll which registers with the upper feed roll, and 45 a pinion formed integral with or rigidly secured to the lower feed roll which meshes with gear wheel 40 on the upper feed roll. The lower feed roll and pinion 45 are mounted to rotate on a stud 46 which extends from an arm 47 and lies loosely in 10 a recess 48 in the body. Arm 47 is pivoted in recess 48 as at 49 and the feed roll and pinion carried by the stud are yieldingly retained in operative position by a spring 50 the ends of which are connected to the outer end of the arm 47 and to the body 20 15 (see Fig. 3 in connection with Fig. 1).

The wire, indicated by 51, is carried by a drum 52 mounted on a screw stud 53 which engages the body. A spring 54 bearing against the head of the stud and against the side of the drum provides the necessary tension therefor. The wire passes from the drum through a guide 55 which straightens it and then between the feed rolls from 25 which it passes into an elongated carrying groove 56 in a rear block 57 which is secured in the body by a screw 59 (see Fig. 4). This groove which is covered and closed by a front block 58 intersects a guide channel 110 in rear block 57 in which the formers and driver, presently to be described, reciprocate. Said guide channel coincides with guide 32 and practically forms a continuation thereof. By providing this carrying groove for the wire between the feed rolls and the cutting off, forming and driving mechanisms, presently to be described, I prevent the possibility of the wire buckling and insure that the exact amount of wire 30 delivered by the feeding mechanism will pass to the operating mechanism without kinks or bends. And furthermore by providing a relatively long convex sector 36 on gear wheel 35 and a corresponding relatively short concave sector 109 on pinion 37, I stop the rotation of the feed rolls the instant the feeding movement is finished and retain them stationary during the rest of the forward movement of the plunger 35 and until near the end of the return movement thereof. At the end of the feeding movement concave sector 109 on the pinion will pass into engagement with the longer convex sector on the gear wheel and during 40 the rest of the forward movement of the plunger the convex sector on the gear wheel will slide over the concave surface of the sector on the pinion, the pinion being thus effectually locked against any movement whatever while the cutting off, forming and

driving operations, presently to be described, are being performed. When the plunger commences to rise or return the convex sector on the gear wheel will slide in the opposite direction over the concave 70 surface of the sector on the pinion, said pinion remaining locked, however, until the sector on the gear wheel has passed out of engagement with the sector on the pinion and the teeth of the gear wheel again engage the teeth of the pinion, which does not take place until near the end of the upward or return movement of the plunger, as will readily be understood from Fig. 3. As the wire is fed forward it passes through 80 a groove 60 in the rear face of a forming block 61 which is socketed in front block 58. The forming block is shown as retained in its socket, indicated by 62, by a top plate 63. The forming block is free to reciprocate transversely to block 58 and is yieldingly retained in its forward or operative position by a spring 64 which is socketed in a recess 65 in the forming block and bears against a face plate 66 which is secured to 90 the body and covers the cutting off, forming and driving mechanisms. The upper rear edge of the forming block is provided with a bevel 67 for a purpose presently to be explained. The forward end of the wire 95 after the feeding movement abuts against the wall of guide channel 110 in block 57 which acts as a stop, as clearly shown in Fig. 8, so that no more wire can be fed into carrying groove 56 until after a staple 100 has been cut off and formed. Should the plunger be allowed to rise or return after a feeding operation and before the cutting off and forming operations and should the plunger again be driven forward the feed 105 rolls would simply slip on the wire, as no wire could be forced into the carrying groove and there would be no danger of the wire buckling or of injury to the machine.

Slide 31 is retained in groove 32 by means of side plates 68 and 69 which are secured to the head by screws 70 which also secure face plate 66 in place, the side plates lying under the face plate. These side plates 115 partly overhang the groove and have important functions which will presently be described. The lower end of slide 31 is shown in Fig. 10 as cut away upon its face, as at 71, and it is furthermore narrowed to form 120 the staple driver 72. If preferred the driver may be made separate from the slide and secured thereto as shown in Fig. 6.

73 denotes a block which slides in groove 32 under the side plates and is provided in 125 its back with a groove 74 in which the driver slides. Extending downward from block 73 are the formers indicated by 75 and 76, which reciprocate in guide channel 110 in block 57. These formers pass downward on opposite 130

sides of forming block 61 (the central portion of the wire for the staple blank lying in the groove in the forming block) and form the staple by bending it to U-shape over the sides of the forming block. The cutting off of the staple blank is performed by a cutter 77 at the outer edge of former 75 (see Figs. 8 and 11) acting in coöperation with the wall of groove 110 in block 57, said wall at the inner end of carrying groove 56 (in which the wire is held against other than longitudinal movement) serving as a stationary cutting off die. It will be noted that the cutter is at the outer edge of former 75 and extends downward slightly below former 76, so that the cutting off of the staple blank from the strip of wire is effected an instant before the formers commence to form the staple about the forming block. An instant after the forming of the staple the driver engages the top of the staple and drives it through the card or other article to be attached and into the article to which it is to be attached, as will be more fully described.

Block 73 carrying the formers and cutter is operated from the slide by means of a hook 78 which is pivoted to the slide as at 79 and is provided at its lower end with a socket 80 which is adapted to receive a stud 81 extending from the block. The inner face of side plate 69 is a straight wall as at 82, and at the lower end of said plate is a downwardly and outwardly extending incline 83. Side plate 68 is provided near its upper end with a shoulder 84 and at a distance below said shoulder with an inwardly extending incline 85 which is adapted to be engaged by a projection 86 on the hook. At the upper end of projection 86 is a shoulder 87 which engages shoulder 84 on side plate 68 to limit the upward or return movement of the slide and the parts carried thereby. In the normal position of the parts as in Fig. 4, stud 81 on block 73 is firmly seated in socket 80 in the hook so that the block, formers and cutter are in fact locked to the slide and move forward with it, the hook being retained in the locking position by the engagement of surface 88 on the hook with straight wall 82 on side plate 69. The parts remain in this position during the forward movement of the slide until projection 86 on the hook engages incline 85 and travels down said incline which forces the hook away from stud 81 as clearly shown in Fig. 5, leaving block 73 and the formers and the cutter wholly disconnected from the slide, incline 83 at the lower end of side plate 69 giving clearance to the hook. The disengagement of the hook from stud 81 will take place the instant the forming operation is completed and the block and formers will then remain stationary. An instant previous to the commencement of the driving op-

eration the lower end of the driver will engage the beveled upper edge of forming block 61 and will force said block backward against the power of spring 64 (see Fig. 10), leaving the formed staple, indicated by 70 108, lying outside of groove 60 and wholly detached from the forming block. At this instant the driver in its forward movement will have reached the top of the staple and the continued forward movement of the slide 75 and driver will drive the staple through the card or notice and into the article to which it is to be attached.

At the completion of the forward movement of the slide and driver, the operator 80 removes his hand from the plunger and spring 33 acts to return the plunger and with it the slide and the parts operated by both plunger and slide to their normal position. As the slide commences to rise or 85 return the hook is carried upward thereby and the engagement of surface 88 on the hook with incline 83 on side plate 69 forces the hook forward into engagement with stud 81 on block 73, projection 86 on the 90 hook riding up incline 85 on side plate 68 and permitting the hook to pass into engagement with the stud, as clearly shown in Fig. 9, in which position it is retained by the engagement of surface 88 on the hook 95 with straight wall 82 on side plate 69. As soon as the hook has passed into engagement with the stud, block 73 and the formers and cutter will be raised to their normal position ready to cut off and form another staple. 100

The operation of the machine as a whole has been so fully described in describing the operation of the mechanisms as to hardly require further description. In brief, the card, tag or other article to be attached is 105 placed in position upon the box or other article to which it is to be attached, the staple driver is placed upon the card or tag with the slide over a place where a staple is to be driven and then a blow upon the 110 rounded head of the plunger is struck with the palm of the hand, driving it forward. The forward movement of the plunger performs the several operations of feeding the wire for a staple, cutting off the staple 115 blank, forming the staple, and driving it, and the return movement of the plunger, which is effected by a relatively light spring the instant the hand is removed from the rounded head or the pressure is relieved 120 merely returns the parts to their normal position. The operation of feeding is performed by feed rolls driven by gearing operated by the plunger. The feed rolls are locked against backward movement by the 125 engagement of a feed pawl with a feed ratchet and the feed driving pinion is locked after each feeding operation through the engagement of a concave sector on the feed driving pinion with a longer convex sector 130

on the gear wheel which drives it, thus rendering movement of the pinion impossible until the gear wheel has passed, during the return movement of the plunger, into position to cause the teeth of the gear wheel to again engage the teeth of the pinion. The staple driver is a part of or is rigidly secured to a slide which in turn is rigidly connected to the plunger. The staple is formed over a sliding forming block provided with a groove to receive it, the formers, one of which is provided with a cutter to cut off the staple blank, are carried by a block which is detachably connected to the slide and is carried forward by the slide until the cutting off and forming operations are completed and is then detached therefrom, the block, formers and cutter remaining stationary while the slide and driver continue their forward movement (the driver displacing the forming block), and drive the staple through the card, tag or notice to be attached and into the article to which it is to be attached. The return movement of the plunger caused by a spring raises the slide and driver, causes the block carrying the formers and cutter to be connected with the slide and raised thereby, and returns the feed pawl, over a tooth of the ratchet, to its normal position ready to feed the wire of another staple. Having driven a staple the body is moved to where another staple is required and another blow is struck upon the rounded head, staples being formed and driven as fast as the blows are struck.

As is clearly shown in Figs. 1 and 2, the outer or free end of arm 30 is connected to the slide 31 by a screw or other suitable detachable fastener, so that when necessary or desirable, the slide can be quickly released from the arm.

Having thus described my invention, I claim:—

1. As an improvement in wire feeding mechanism, the combination with a head and a plunger mounted in said head, of wire feeding mechanism actuated by said plunger and including interengaging complemental members having means for interrupting the wire feeding functions when a predetermined quantity of wire has been fed, and means for permitting the wire feeding members to slip with respect to the wire when the feeding movement is interrupted.
2. As an improvement in wire feeding mechanism, the combination with a head

and a plunger mounted in said head, of wire feeding rolls, means actuated by said plunger for operating said feed rolls, said operating means including interengaged complemental members for permitting the rolls to slip when feeding movement of the wire is completed.

3. As an improvement in wire feeding mechanism, the combination with a head and a plunger mounted in said head, of wire feeding mechanism actuated by said plunger, said wire feeding mechanism including a drive pinion, an operating pinion meshing with said drive pinion, said pinions being provided with complemental smooth sector portions for interrupting the wire feeding functions when a predetermined quantity of wire has been fed, and means actuated by said plunger for driving said operating pinion.

4. As an improvement in wire feeding mechanism, the combination with a head and a plunger mounted therein, of wire feeding mechanism actuated by said plunger, said wire feeding mechanism including a drive pinion, an operating pinion meshing with said drive pinion, said drive pinion being provided with a relatively small smooth sector portion, said operating pinion being provided with a relatively large smooth sector portion coöperating with the sector portion of the drive pinion to render the feeding mechanism inoperative when a predetermined quantity of wire has been fed, and means actuated by said plunger for driving said operating pinion.

5. As an improvement in wire feeding mechanism, the combination with a head and a plunger mounted therein, of an arm pivoted to said head at one end, means for resiliently supporting the other end of said arm, feed rolls one of which is supported by said arm, a drive pinion for actuating said feed rolls, and an operating pinion rotated by said plunger and meshing with said drive pinion, said pinions being provided with complemental smooth sector portions for interrupting the wire feeding functions when a predetermined quantity of wire has been fed.

In testimony whereof I affix my signature in presence of two witnesses.

LEWIS R. HEIM.
